UNITED STATES PATENT OFFICE

WILLIAM B. WATKINS, OF JERSEY CITY, NEW JERSEY.

IMPROVEMENT IN ELECTRIC CIRCUITS FOR FIRE AND POLICE TELEGRAPHHS.

Specification forming part of Letters Patent No. 172,219, dated January 11, 1876; application filed November 23, 1872.

To all whom it may concern:

Be it known that I, WILLIAM B. WATKINS, of Jersey City, State of New Jersey, have invented certain new and useful Improvements in Electric-Telegraph Circuits for Fire, Police, and Burglar Alarm, and other Telegraphic Purposes; and I do hereby declare that the following is a full description of the same.

The great objection to the use of the ordinary closed metallic circuit for transmitting signals to a main or central station for telegraphic or signaling purposes is, that when a break on the line occurs, and while it remains open, the instruments in such a circuit cannot be used, and signals cannot be transmitted to or received from the central station until the line is electrically repaired; and the same is true of the instruments in such a circuit when any of them are short-circuited or cut out. The same is also true of a portion of the line-instruments when a break or short circuit occurs in the ordinary earth or Morse circuit in common use for telegraphic purposes.

When such circuits are used for transmitting signals to a central or receiving station, for fire, burglar, or police alarm purposes, the delay occasioned in electrically repairing the line when such accidents occur, and the time lost, are often the cause of great loss of life and property.

My improvement in telegraph-circuits not only overcomes the foregoing objections, but at the same time doubles the capacity of a main metallic circuit when it is clear, so that two separate and distinct sets of signals, or two separate dispatches, may be transmitted or received at the same instant over the one main metallic circuit.

My invention consists, first, in combining with a main metallic circuit the following elements, viz: a permanent earth-connection having an auxiliary battery and receiving-instrument, and at various points on the metallic circuit a series of normally-open earth-branches, with suitable signaling-instruments placed in or connected with the latter and with the metallic circuit, whereby, when any one of the signaling-instruments is operated, an earth-circuit may be established at intervals, and a signal sent to the receiving-instrument of the permanent earth-connection, and

at the same instant the metallic-circuit instruments may be used for communicating intelligence, using the same main wire without interfering with the operation of the earth-circuit instruments, and whereby, when a break occurs in the metallic circuit, signals may be sent from all points of the open metallic circuit, on both sides of the break, by means of the earth-connections and signaling-instruments connected therewith, and whereby the same may be done when the metallic circuit is short-circuited, or when both broken and short-circuited; secondly, in combining, with the elements above set forth, an alarm-instrument with a receiving-instrument of the metallic circuit, which alarm will be operated whenever the metallic circuit is broken, so that the line may be kept intact for the purposes set forth; thirdly, in combining magnets and switches with the open earth-branches and metallic circuit, so that the use of the same for telegraphic purposes may be more effectually carried out.

But, to describe my invention more particularly, I will refer to the accompanying drawings, forming a part of this specification, the same letters of reference, whenever they occur, referring to like parts.

Figure 1 is a plan view of the arrangement of the magnets, batteries, circuit of wires, stations, and earth-circuits composing the main and auxiliary circuits, to illustrate the use of the said auxiliary circuit in combination with a main circuit of wires.

Letter A is a station for receiving signals, represented within the lines B, having the circuit or line C connecting with the + pole of the battery D, magnet E, and key F, and thence running to station G, it connects with the binding-screw H, magnet I, key J, binding-screw K, and, leaving the station, it connects with such instruments as may be required for various telegraphic purposes in the buildings or stations, No. 3, No. 4, No. 5, No. 6, No. 7, or any other number desired. The line returns to the - pole of the battery D at the station A, forming a closed metallic circuit. The magnet E may be used for operating, or bringing into operation, telegraphic instruments of any description, and for any purposes required. The armature L, by suitable connections, may be

made to act as a relay, to operate a local circuit, or a local-alarm instrument, which, in a well-known manner, will ring a continuous alarm when the circuit C is broken, so that the condition of the line may be known at all times. Such a local-alarm circuit is shown, and runs from the post M through the wire N, spring G, vibrating lever P, magnet Q, and battery R, to the armature and lever L. The circuit C now being complete, the branch S is attached to any point of the line on either side of the magnet E or battery D. This branch connects with a closed key, T, with the coils of a magnet, U, battery V, and the earth W.

The magnet U may be used to operate, or bring into operation by the movements of its armature X, such instruments as may be required for all the various telegraphic purposes, such as for sounding and recording the signal numbers of buildings or stations where a fire or burglary has been discovered or is taking place; or both magnets E and U may be used to operate, or bring into operation, a printing-telegraph of any desired construction when one magnet is used to move a type-wheel, so as to bring letters or characters in a position to print impressions of the same upon paper by the movements of another armature; or each magnet may be used to operate a separate dial telegraph-instrument, in a well-known manner. At the station G, and all the other stations, there is a switch, b², which may turn loosely, so as to remain open, as shown; or it may be a spring-switch, which will keep closed on the button c², except when fastened or pressed away. This switch should always remain open when signals or messages are to be received from the main station A; but for all purposes where the station A is used only to receive messages or signals, such as fire, burglar, or police alarms, the switch b² should be turned as shown by the dotted lines on the button c², which, connecting with the branch d², will then cut out the magnet I and key J. If this is so arranged at each station, the resistance of the line C will be so reduced that a great number of stations may be connected with the circuit, and there will be no keys or magnets in the line outside the main station, except when a message is to be sent; then the switch b² will be opened, as shown, and if the magnet I is not in use—which will be known if the armature e² is not operating—then the desired message or signal may be transmitted to, and answers received from, the station A. The whole force of the battery D will be through the magnets in use only, (E and I in use in this instance,) and will be so powerful that local batteries in any of the buildings or stations outside the main station will not be required. This arrangement of switches is shown and fully described in Letters Patent granted to me January 31, 1871.

At the station G, from any point of the line C or from any of its connections, a branch line, f², is run through the coils of the mag-

net g² to the spring or key h², which, by the force of the spring, remains open, as shown. The metallic point i² connects with the earth j².

Now, it will be seen that these branch wires, either with or without the magnet g², form a normally open earth-branch, and with such branches at the various stations, and with fire-alarm or other signaling boxes suitably connected and set in motion, the circuit may be completed at intervals from the main metallic circuit through either of the earth-connections to the earth-battery V, and through the receiving-instrument U, so that the desired signal will be received at the main station A.

Now, when the spring or key h² is alternately closed and opened, either by an operator or by mechanical or electro-magnetic mechanism arranged for the purpose, the armature k² at station G and armature X at station A will be operated simultaneously, for any desired telegraphic purpose, without affecting the circuit C. The current of the auxiliary earth-circuit, when the spring h² is closed, will find the path of least resistance. Assuming this to be from the — pole of battery D, in the direction of the arrow, the course of the current will be from the + pole of the battery V, through the coils of the magnet U, key T, branch S; thence in the direction of the arrow m² to the screw-post K, through the coils of magnet g², earth j², and earth W, to the — pole of the battery V. If the resistance be equally divided from both sides of the permanent earth-branch S to the screw-post K, the result will be the same. The current will then take the two paths each side of S, and will unite at K, from which the circuit will be completed, as before. In both cases the armature L of the magnet E and the armature e² of the magnet I will not be affected, as the metallic circuit C will not be broken.

At station No. 7 the connections shown are similar to those at station G. The magnet n² and key o² connect with the line or metallic circuit C, and the magnet p² and key q² are to be used in connection with the normally open earth-branch r².

As an illustration of some of the advantages in telegraphy which may be derived from this arrangement of circuits, let operators be stationed as follows, viz: Let s² and t² be at station G with suitable signaling-instruments. Let u² and v² be at the main receiving-station A, and let w² and x² be at station No. 7 with suitable signaling-instruments. Now, it will be seen that s² and u², by means of the earth-connections and instruments connected therewith, can communicate telegraphically with each other; or signals can be sent by s² over the metallic circuit, or over the longest arm thereof, when the metallic circuit is broken at key J by operator t²; and at the same time t² and v², by the use of the keys J and F of the metallic circuit C and the magnets E and I, can also communicate telegraphically with each other—that is to say, the ca-

capacity of the line C is doubled by the use of the auxiliary earth-battery and normally open earth-branches connected therewith.

It will be further seen that operators x^2 and v^2 can communicate with each other, while at the same instant w^2 and u^2 can also communicate with each other. Now, if the metallic circuit C be broken accidentally, as at the point y^2 , the vibrating alarm-bell z^2 at the station A will be sounded by the vibrating lever P, because the breaking of the circuit C releases the armature L of its receiving-magnet E, and this closes the local-alarm circuit at M. Now, the use of the metallic circuit C necessitates the breaking of it at intervals by an operator, when he uses his key by opening it. The circuit then becomes divided. When broken accidentally, as at y^2 , it then becomes divided into two open arms of insulated wires, each connected permanently with the earth-battery V and receiving-instrument U, the wire connecting with and running from the battery V in the direction of the arrow m^2 , having the series of open earth-branches provided with suitable signaling-instruments at stations 3, 4, 5, 6, and 7, and the other arm or wire having the open earth-branch i^2 at station G.

Now, instantly that a break has occurred, and a message or signal has to be sent from station No. 7 to the receiving-station A, this can be done notwithstanding the break, for it will be seen that by the use of the open earth-branches operator w^2 or s^2 can instantly communicate with u^1 ; or, by the use of suitable signaling-instruments, signals may be sent from any of the open earth-branches on either side of the break, and will be received on the earth-connected instrument U before the break has been repaired. The break having been repaired, let an accidental ground occur at any point of any of the auxiliary branches, as at b^3 , station No. 7. This will not interfere with the working of the instruments in the metallic circuit C, as it will be seen that by opening the switch b^2 at any or all of the stations any two of the operators, as at x^2 , t^2 , and v^2 , can communicate with each other. Now, remove the ground b^3 , and let a short circuit occur, as at the points c^3 and d^3 . It will be seen that with the ordinary arrangement of the metallic circuit C, without the improvements of the earth-connections, as described, stations No. 4, No. 5, No. 6, and No. 7 could not transmit signals to nor communicate with the main station A, but would be cut out entirely until the short circuit was removed; but by my arrangement these stations can, by means of the auxiliary earth-connections, and suitable signaling-instruments, communicate with the main station A, and at the same time all the other stations can communicate with each other the same as if the short circuit had not occurred.

It will thus be seen that inasmuch as the metallic circuit is normally closed, it follows that when an operator wishes to telegraph

over it for any purpose by the use of the metallic-circuit instruments, he must begin by opening it, and must transmit his dispatch by alternately opening and closing it; but when this circuit is thus opened, it then consists for the time being of two open arms, or, in other words, two wires, connected with the one permanent earth-battery. This, however, does not render any part of the line inoperative during the continuance of such break, for whenever any open earth on one arm is closed the ground-circuit on that side of the break will be complete without regard to the break, and whenever an open earth on the other side of the break is closed the same will be true on such other side of the break. A break, therefore, however long continued, and whether by design or by the accidental severing of the wire, does not in any way interrupt or interfere with the perfect operation of the fire-alarm portion of the line; and the same will be true when the line is short-circuited, or when it is at the same moment both short-circuited and broken.

At the different stations there is a switch, e^3 , as shown at station G, which is forced away from the button f^3 by means of the spring g^3 . When messages are to be received from station A, this switch must be held on the button f^3 by the operator, so that the branch will be closed, as shown by the dotted lines, or else the key h^2 may be pressed on the metallic point i^2 . When not in use, the releasing of either the key or spring h^2 , or the switch e^3 , will leave the auxiliary branch in its normally open condition, so that any other open earth-branch may be used to transmit signals to the receiving-station A. If v^2 and t^2 are in communication, and v^2 wishes to call s^2 , he directs v^2 to notify t^2 to instruct s^2 , and the latter immediately closes the key h^2 or switch e^3 , and receives the communication from v^2 on the earth-connections, without interfering with the operations of v^2 and t^2 on the metallic circuit. The switch g^3 is to be used in connection with the earth h^3 when necessary, for dividing the metallic circuit into two separate circuits, so that each may have an independent earth-battery; also for locating grounds or other faults, and for throwing off, when necessary, a portion of the metallic circuit when accidentally broken and grounded.

It will be obvious that the foregoing-described combination of circuits constitutes a double-acting circuit, which is capable of being applied for all the various purposes of telegraphy by the use of suitable instruments in combination therewith, among which may be mentioned signaling-instruments for fire, police, burglary, messenger, domestic, and safety railroad signaling purposes, and for public and private telegraphy.

Full descriptions of the same will accompany other applications for patents to complete the series of inventions in connection with my improved double-acting circuit hereinbefore described.

I claim—

1. In combination with a metallic circuit, C, (including its battery and instruments,) the auxiliary earth-battery V and its receiving instrument, connected with the earth or ground W, and with the metallic circuit, and a series of earth-branches, i^2 , j^2 , and r^2 , normally open, but having suitable signaling-instruments connected therewith and with the metallic circuit, for the purposes set forth.

2. An insulated metallic electric wire, provided with a battery, and having two or more earth-connections normally open, and also a permanent earth, with a battery connected to the wire between said normally open earths, whereby signals can be sent along the insulated wire in either direction to and from said battery, substantially as described.

3. In combination with both arms of a broken metallic circuit, C, and suitable telegraph-instruments for closing and opening the same,

a permanent earth-battery, V, and receiving-instrument operated thereby, and one or more signaling-instruments connected with the insulated wires, but each having an earth-connection normally open, the whole forming a double-acting telegraph, for the purposes set forth.

4. In combination with the metallic circuit C and earth-circuits, as set forth, one or more magnets, g^2 and p^2 , in the earth-branches.

5. In combination with the metallic circuit C and earth-circuits, as set forth, the switch g^3 and earth h^3 , for the purposes described.

6. In combination with the combined circuits, an alarm apparatus in connection with the armature L of the receiving-instrument E.

WILLIAM B. WATKINS.
